UNITED STATES PATENT OFFICE.

STEWART L. BERGSTRESSER, OF LAURELTON, ASSIGNOR TO J. B. BERGSTRESSER, OF RENOVO, AND E. L. BERGSTRESSER, OF HUBLERSBURG, PENNSYLVANIA.

IMPROVEMENT IN PHOTOGRAPHIC-PLATE HOLDERS.

Specification forming part of Letters Patent No. 159,537, dated February 9, 1875; application filed August 3, 1874.

To all whom it may concern:

Be it known that I, STEWART LEE BERGSTRESSER, of Laurelton, in the county of Union and State of Pennsylvania, have invented certain new and useful Improvements in Photographic Apparatus; and I do hereby declare the following to be a full, clear, and exact description of the invention, such as will enable others skilled in the art to which it pertains to make and use it, reference being had to the accompanying drawings, which form part of this specification.

My invention relates to an improvement in photographic apparatus; and it consists in, first, forming a rim or flange around three sides of the plate-holder, so as to catch over the top and sides of the movable part of the camera, and thus exclude all light from the prepared sensitized plate; second, a flexible screen for excluding light from the sensitized plate while in the plate-holder, and being carried back and forth from the camera; third, guides placed in the plate-holder, whereby the holding devices for the plate can be adjusted up and down to suit different-sized plates; fourth, forming the plate-holder from a square box, which is open at its front only, so as to dispense with both the hinged door and slide heretofore used; fifth, a zinc box in which is placed the silver-box, so as to catch any silver that may be accidentally spilled from the silver-box, and which box can be adjusted up and down in the plate-holder at will; sixth, the arrangement and combination of devices which will be more fully described hereafter.

The accompanying drawings represent my invention.

The plate-holder *i* consists of a flat square box of suitable depth, which has a flange or rim, *j*, formed around three of its sides, which rim fits over the top and sides of the rear end of the camera, and thus effectually prevents the entrance of a single ray of light to the plate. This box is open at its front side only where the plate is inserted, and this opening is closed by means of a flexible screen, *l*, which has its ends connected together by two belts,

n, which pass around suitable rollers *m*, placed at each side of the box. By means of this screen the plate-holder is kept closed while carrying the plate back and forth from the camera, and I am enabled to dispense with both the hinged door and slide heretofore used. This screen may be made of any suitable material, and made to pass around rollers, as shown, or simply to operate in ways or guides prepared for it. To the back of the plate-holder are secured the two ways or guides 1, upon which the devices for supporting the prepared plate in position can be adjusted up and down, the devices having suitable catches, which catch behind the guides 1. By slipping the devices up or down to the openings 2, cut in the inner sides of the guides, they can be readily removed from and inserted into position. The lower device consists of a silver-box, 3, of any suitable construction, in which the lower end of the plate rests, so as to catch the drippings of silver. This silver-box is placed in a somewhat larger box, 4, made of zinc, and lined with blotting-paper, or other absorbent material, which catches any silver that may be accidentally spilled from the silver-box. This box has a slot cut in its upper edge, through which passes a set-screw, by means of which it can be adjusted up and down at will. The upper device, 5, is provided with a sliding bolt, 6, which has suitable catches 7, for catching over the top of the plate, and holding it in position, and a spring, 8, for throwing the bolt up when released. Back of the glass is placed a spring absorbent pad or cushion, 9, which keeps the plate pressed outward, so as to keep it from moving about.

If desired, the device 5 can be operated by a screw instead of as described.

Having thus described my invention, I claim—

1. A plate-holder having a rim or flange formed around its edges, so as to catch over the rear end of the camera, and prevent the admission of light to the plate, substantially as specified.

2. A plate-holder provided with a flexible screen, substantially as shown and described.
3. A plate-holder closed on all sides except the one where the picture is inserted, substantially as set forth.
4. A plate-holder closed upon all sides except one, and provided with a flexible screen, substantially as described.
5. A zinc box for holding the silver-box, the said zinc box being made adjustable up and down, substantially as specified.
6. A plate-holder provided with a flexible

screen and rollers, around which the screen passes, substantially as set forth.

7. The spring absorbent pad 9, substantially as specified.

In testimony that I claim the foregoing I have hereunto set my hand this 31st day of July, 1874.

S. L. BERGSTRESSER.
